(57) CLAIM

We claim the ornamental design for game card case, as shown and described.

DESCRIPTION

FIG. 1 is a front, left perspective view of the game card case, in a first embodiment, showing our new design;

FIG. 2 is a rear, left perspective view thereof;

FIG. 3 is a front elevation view thereof;

FIG. 4 is a rear elevation view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a front, left perspective view thereof, in a folded configuration;

FIG. 10 is a front, left perspective view thereof, in a folded configuration;

FIG. 11 is a front, left perspective view of the game card case in a second embodiment, showing our new design;

FIG. 12 is a rear, left perspective view thereof;

FIG. 13 is a front elevation view thereof;

FIG. 14 is a rear elevation view thereof;

FIG. 15 is a left elevational view thereof;

FIG. 16 is a right elevational view thereof;

FIG. 17 is a top plan view thereof;
